DESIGN FOR AN ASH TRAY OR SIMILAR ARTICLE

Garfield L. Beckstrom, Chicago, Ill., assignor to Autopoint Company, Chicago, Ill., a corporation of Illinois

Application October 25, 1944, Serial No. 115,960

Term of patent 14 years

(Cl. D85—2)

To all whom it may concern:

Be it known that I, Garfield L. Beckstrom, a citizen of the United States, residing at Chicago, in the county of Cook and State of Illinois, have invented a new, original, and ornamental Design for Ash Tray or Similar Article, of which the following is a specification, reference being had to the accompanying drawing, forming a part thereof.

In the drawing:

Fig. 1 is a side elevation of an ash tray or similar article embodying my design.

Fig. 2 is a top plan view thereof.

Fig. 3 is an end elevation looking toward either the right hand side or left hand side of Fig. 1.

I claim:

The ornamental design for an ash tray or similar article, substantially as shown.

GARFIELD L. BECKSTROM.
